UNITED STATES PATENT OFFICE.

HENRY P. SABBERT, OF OAKLEY, ASSIGNOR TO KROEGER, SABBERT & CO.,
OF CINCINNATI, OHIO.

TABLE-TOP.

SPECIFICATION forming part of Letters Patent No. 329,086, dated October 27, 1885.

Application filed August 18, 1884. Serial No. 140,844. (No model.)

To all whom it may concern:

Be it known that I, HENRY P. SABBERT, a citizen of the United States, and a resident of Oakley, in the county of Hamilton and State 5 of Ohio, have invented certain new and useful Improvements in Table-Tops, of which the following is a specification.

This invention relates to tops for tables, desks, and similar articles of furniture. Its 10 object is to produce a cheap, durable, and cleanly surface, that may also be made highly ornamental at a very small additional cost.

With these objects in view my invention consists in a transparent plate of glass or similar 15 hard smooth substance, embedded in or upon the top of the article on a cushion of some yielding material placed underneath and around the edge under the confining molding or top finishing-strip, so as to leave an air- 20 space between the glass and the table-top, which is covered with velvet, silk, plush, or some ornamental finish to give it an attractive appearance.

In the accompanying drawings, in which 25 similar reference-letters indicate like parts wherever they occur in the different views, Figure 1 is a top plan view of a table-top provided with my improvements. Fig. 2 is a central vertical section through the same.

The outside frame, A, may be made of any 30 suitable pattern or design, but is preferably built up of several pieces, the different layers having their joints broken, so as to insure strength and prevent warping. The bed or 35 top B fits snugly within the frame A, and is covered with velvet or similar fabric, which may, if desired, be ornamented in any suitable manner. Around the edge of the top B is a narrow frame of some elastic or yielding 40 material—such as rubber or paper-board. Upon this frame C the glass plate D is supported and held by the overlapping inner edge or molding, a, of frame A. A little space is left between the inner edge of frame A and 45 the outer edge of plate D to allow for the expansion or contraction of the glass plate under different temperatures. The space between the plate D and velvet covering E prevents moisture from condensation injuring the 50 velvet, and also insures the velvet or other covering retaining its glossy rich appearance,

which would not be the case if the glass rested directly upon it. The glass plate has its under side ornamented in any suitable manner, preferably by engraving and afterward filling 55 the graven design with gold, silver, or other suitable ornamental material. Underneath the beveled edges d the plate is silvered and the coating protected by the customary covering, so that it would not be injured by resting 60 upon the narrow frame C.

In practice I make the frame of the table as shown, having the rabbet around the inner frame, so that the table can be completely finished before the insertion of the top, which 65 after it is finished is slipped in from the under side, and the top B secured to the frame A in any suitable manner; but, if desired, the table with its bed-plate B may be made complete and finished, and afterward the top-plate 70 B placed in from above. In this case of course the molding a of top-finishing rim-frame A would be separated from the table-top and secured on after the plate was in place.

It will be seen that my improved top has 75 all the advantages of cleanliness of the marble top and at the same time is capable of being highly ornamented without danger of the ornamented parts being injured, and the velvet finish beneath gives it a warm rich appearance, and thus overcomes the principal objection now urged against marble-top tables, which is that they have a cold, hard appearance. It is evident that the fabric E may also be embossed to suit the taste or fancy of 80 the designer, and that instead of the velvet or other fabric the top may be enameled or inlaid and the glass left plain. In this case the table-top would have the appearance of the richly inlaid or ornamented tops now so much in 85 favor, and the ornamented surface would at the same time be protected and the table kept clean.

Prior to my invention it was common to make tops for tables and similar articles of 90 glass placed above and resting upon a bed of ornamented paper or other material. I make no claim to such construction.

What I claim as new, and desire to secure, is—

1. A top for tables, desks, and similar articles, consisting of an outer frame, a lower

bed-plate ornamented or covered with an ornamental material, an upper transparent plate, and an intervening frame separating the transparent plate and the ornamental plate beneath it, substantially as described.

2. In a table-top, the combination, substantially as specified, of the outer frame, A, bed-plate B, sunk below the upper edge of said frame A, with the frame C, arranged around the bed B and against the edges of frame A

and separating the bed B and plate D, with the covering E of velvet or other suitable material, and the beveled edged glass plate D, resting upon said frame C and held in place by the overhanging molding a.

HENRY P. SABBERT.
